CLAIM

The ornamental design for a spine for troffer light fixture, as shown and described.

DESCRIPTION

FIG. 1 is a front perspective view of a first embodiment of a spine for troffer light fixture;

FIG. 2 is a top plan view thereof;

FIG. 3 is a bottom plan view thereof;

FIG. 4 is a front elevation view thereof;

FIG. 5 is a rear elevation view thereof;

FIG. 6 is a left-side elevation view thereof;

FIG. 7 is a right-side elevation view thereof;

FIG. 8 is a front perspective view thereof with additional broken line environment;

FIG. 9 is a front perspective view of a second embodiment for the spine for troffer light fixture;

FIG. 10 is a top plan view thereof;

FIG. 11 is a bottom plan view thereof;

FIG. 12 is a front elevation view thereof;

FIG. 13 is a rear elevation view thereof;

FIG. 14 is a left-side elevation view thereof; and,

FIG. 15 is a right-side elevation view thereof.

The broken lines shown in the drawings are for the purpose of illustrating portions of the article that form no part of the claim design.

1 Claim, 7 Drawing Sheets
